(57) **CLAIM**

The ornamental design for an alphabet toy set, as shown and described.

DESCRIPTION

FIG. 1 is a front view of an alphabet toy set showing my new design;

FIG. 2 is a front view of an enlarged view of the letter "A" in FIG. 1;

FIG. 3 is a front view of an enlarged view of the letter "B" in FIG. 1;

FIG. 4 is a front view of an enlarged view of the letter "C" in FIG. 1;

FIG. 5 is a front view of an enlarged view of the letter "D" in FIG. 1;

FIG. 6 is a front view of an enlarged view of the letter "E" in FIG. 1;

FIG. 7 is a front view of an enlarged view of the letter "F" in FIG. 1;

FIG. 8 is a front view of an enlarged view of the letter "G" in FIG. 1;

FIG. 9 is a front view of an enlarged view of the letter "H" in FIG. 1;

FIG. 10 is a front view of an enlarged view of the letter "I" in FIG. 1;

FIG. 11 is a front view of an enlarged view of the letter "J" in FIG. 1;

FIG. 12 is a front view of an enlarged view of the letter "K" in FIG. 1;

FIG. 13 is a front view of an enlarged view of the letter "L" in FIG. 1;

FIG. 14 is a front view of an enlarged view of the letter "M" in FIG. 1;

FIG. 15 is a front view of an enlarged view of the letter "N" in FIG. 1;

FIG. 16 is a front view of an enlarged view of the letter "O" in FIG. 1;

FIG. 17 is a front view of an enlarged view of the letter "P" in FIG. 1;

FIG. 18 is a front view of an enlarged view of the letter "Q" in FIG. 1;

FIG. 19 is a front view of an enlarged view of the letter "R" in FIG. 1;

FIG. 20 is a front view of an enlarged view of the letter "S" in FIG. 1;

FIG. 21 is a front view of an enlarged view of the letter "T" in FIG. 1;

FIG. 22 is a front view of an enlarged view of the letter "U" in FIG. 1;

FIG. 23 is a front view of an enlarged view of the letter "V" in FIG. 1;

(Continued)

FIG. 24 is a front view of an enlarged view of the letter "W" in FIG. 1;
 FIG. 25 is a front view of an enlarged view of the letter "X" in FIG. 1;
 FIG. 26 is a front view of an enlarged view of the letter "Y" in FIG. 1; and,
 FIG. 27 is a front view of an enlarged view of the letter "Z" in FIG. 1.
 The alphabet toy set is flat and the undisclosed sides, top, bottom, and rear views form no part of the claimed design.
